UNITED STATES PATENT OFFICE.

JULIAN KENNEDY, OF PITTSBURGH, PENNSYLVANIA.

STEAM ENGINE.

Application filed February 23, 1922. Serial No. 538,620.

Figure 1 is a longitudinal sectional view through an engine cylinder embodying the present invention, certain of the parts being illustrated in section;

5 Figure 2 is a sectional detail view on an enlarged scale;

Figure 3 is a diagrammatic view illustrating an indicator card curve;

10 Figure 4 is a view corresponding to Figure 1 illustrating a slightly modified form of the present invention;

Figure 5 is an end elevation partly in section, of the construction illustrated in Figure 4;

15 Figure 6 is a detail sectional view of a portion of the valve operating means;

Figure 7 is a diagrammatic view, corresponding to Figure 3, illustrating the relationship between the curves for opposite ends 20 of the cylinder, and

Figure 8 is a diagrammatic view illustrating one form of valve gear for controlling the steam admission valves.

The present invention relates broadly to 25 steam engines and more particularly to steam engines of the uniflow type.

Due to the economy of operation of uniflow engines, it is very desirable under a good many conditions to make use of such engines.

30 A serious objection, however, to such use has been the fact that it has heretofore not been possible to reverse the same at any desired point during the cycle of operation.

By the present invention, I have provided 35 a construction by means of which it is possible to reverse a uniflow engine at any point in the stroke during the operation thereof, thereby overcoming existing objections to the use of such engines.

40 Referring more particularly to Figures 1 to 3 of the drawings, there is illustrated a portion of a uniflow engine comprising a cylinder 2 having a piston 3 and piston rods 4, operable through the stuffing boxes 5 at each 45 end of the cylinder. Intermediate the ends of the cylinder there are provided a series of exhaust openings 6 communicating with an exhaust port 7, by means of which the expanded steam is permitted to escape from the 50 engine cylinder as soon as the piston uncovers the exhaust openings.

Cooperating with the cylinder 2 is a steam admission chamber 8, having an inlet port 9. Adjacent each end of the chamber 8 there is 55 provided a steam inlet port 10 communicating with the interior of the cylinder 2. The

admission of steam from the chamber 8 to the cylinder 2, through the ports 10, is controlled by means of piston valves 11 carried by a valve-operating rod 12.

60 In Figure 1 of the drawings the piston 3 is illustrated as having just completed its travel to the right-hand end of the cylinder, the expanded steam having been permitted to escape through the exhaust openings 6. Continued operation of the engine will cause the

65 valve-operating rod 12 to move to the right, thereby uncovering the port 10 and permitting the passage of steam into the right-hand end of the cylinder. This steam will be effective for producing travel of the piston toward the left-hand end of the cylinder. As

70 soon as the desired amount of steam has been admitted, the valve-operating rod will again travel to the left and close the ports 10. Re-

75 ferring to the chart indicated in Figure 3, it will be apparent that steam is admitted at approximately the point A and is cut off at approximately the point B. During the

70 travel of the piston from the point B to the point C, the steam will be expanding as is customary. At the point C, the exhaust

75 openings will be uncovered and the steam released, the exhaust openings remaining uncovered from the point C to the point D. The

80 return movement of the piston from the point D to the point A will result first in a gradual compression, and then a rapid compression to produce a compression in the cylinder

85 substantially equal to the pressure of the entering steam to thereby obviate any hammering. These operations will be repeated for

90 each end of the cylinder during each cycle of operation.

95 If it were attempted to reverse an engine of the character described, without releasing the steam now expanding in one end of the cylinder, such trapped steam would be recom-

100 pressed, and, if the engine were under any load, reversal would not be possible. In the

105 construction disclosed, however, I have provided means for relieving the pressure in one end of the cylinder when it is desired to reverse the direction of travel of the piston.

110 Referring more particularly to Figures 1 and 2 of the drawings, it will be noted that there is provided adjacent each end of the chamber 8 a port 13 leading to the space 14 below the valve 15. The valve 15 is prefer-

115 ably loaded to any desired degree by a spring 16, or equivalent means, whereby the valve will only open when it is subjected to the pre-

determined pressure. Adjusting means 17 may be provided for varying the point at which the valve will open. Assume that the piston 3 is traveling toward the left as viewed in Fig. 1 and that it has passed the point of cut-off, the valve 11 will be in such position that the port 10 is isolated from the chamber 8 and, during the major portion of the stroke, the port 10 will be completely closed so as to 10 permit expansion of the steam in the cylinder. If it is desired to reverse the engine the valve rod 12 will be moved to the left so as to bring the reduced portion 11 of the piston valve over the port 10 and thus establish communication between the port 10 and the port 13. This will immediately permit the steam in the right-hand end of the cylinder to exhaust therefrom by lifting the valve 15 and escape either to the atmosphere or to the 20 condenser depending upon the connections to the valve. The movement of the valve-operating rod 12 to the left will also be effective for uncovering the port 10 at the left-hand end of the cylinder and thereby admit steam for 25 producing the travel of the piston in the opposite direction. The movement of the valve which is required for reversing the engine may be accomplished by any suitable reversing mechanism as, for example, the well 30 known Stephenson reversing link gear.

Referring to Figure 3, it will be assumed that the piston has reached the point corresponding with the point E in the expansion curve, and that it is desired to reverse the direction of travel of the piston. The valve-operating rod will be moved as described, and immediately the pressure of the steam which was undergoing expansion will drop as indicated by the chain line F to the pressure represented by the chain line G. It will be obvious that the pressure indicated by the chain line G may vary in accordance with the loading of the particular valves, and that in the drawing the relation between this pressure line and the absolute vacuum line is for purposes of illustration only. In this figure I have also illustrated the pressure drop which will occur if the engine is reversed when the piston has reached a point in its travel corresponding to the point H.

Referring to Fig. 1 which shows the piston as having just completed its stroke to the right, it will be seen that the valve rod 12 must be moved to the right so as to establish communication between the chamber 8 and the port 10 in order to allow admission of steam to the right hand end of the cylinder. It will be seen from Fig. 1 that this movement of the valve rod 12 necessarily results in the 60 port 10 at the left hand end of the cylinder being placed in communication with the corresponding port 13 at the left hand end of the cylinder. As pointed out, however, the relief valve is spring loaded and of course the 65 pressure in the left hand end of the cylinder

at this time is quite low. In consequence no steam escapes through the relief valve and before the cushioning pressure in the left hand end of the cylinder has been built up to a point corresponding to the "blow off" pressure of the relief valve, the valve rod at 10 will have again moved to the left in such amount as to isolate the relief valve from the cylinder. It will be apparent, therefore, that my improved construction does not interfere 75 with the normal operation of a uniflow engine but does provide means whereby such an engine may, at any time during its operation, be reversed by establishing in one end of the cylinder a pressure corresponding to the 80 pressure at which the valve 15 is set. This results automatically by the release of the trapped steam from the end of the cylinder in which steam expansion has just been taking place. 85

In Figures 4 to 7 I have illustrated a modified form of my invention adaptable for use with engines of the uniflow type having poppet valves controlling the admission of steam. In this form of my invention the 90 cylinder 20 has a series of centrally arranged exhaust openings 21 communicating with the exhaust port 22, as before described. The piston 23 carried by the piston rod 24 is adapted to reciprocate in opposite directions in accordance with the admission of steam to the cylinder. Such admission is controlled by a poppet valve 25 adjacent the left-hand end of the cylinder controlling the passage of steam from the inlet port 26 to the cylinder 100 and by the poppet valve 27 adjacent to the right-hand end of the cylinder controlling the admission of steam thereto from the inlet port 28. 95

In addition to the inlet valves 25 and 27, 105 there is located adjacent each end of the cylinder an auxiliary valve mechanism comprising a poppet valve 29 adapted to open inwardly and held normally in closed position by a suitable compression spring 30 surrounding the valve stem 31. These valves are adapted to be opened in timed relation with the operation of the engine against the action of the springs 30 by cams 32 mounted on sleeves 33 into which pass the ends of the cam shafts 34. At their outer ends the cam shafts 34 are each provided with a bevel gear 35 meshing with a second bevel gear 36 carried by the shaft 37. The shaft 37 is of the type ordinarily provided with uniflow engines and carries the eccentrics 38 for opening the poppet valves 25 and 27. The valve gear for accomplishing this movement is duplicated for each of the valves 25 and 27, and comprises an arm 39 actuated by the eccentric 38 115 and pivotally secured to a rocker segment 40. The rocker segment in turn has a pivotal connection 41 carried by one arm of an adjusting lever 42, whereby the position of the pivotal mounting for the rocker segment may 120 125 130 135

be varied to vary the point of admission and the point of cut-off of the live steam. Mounted in the slot 43 of the rocker segment is a slide 44 secured to the lower end of the link 5 45, the upper end of which link is operatively secured to a cam 46 for actuating one of the steam inlet poppet valves.

When it is desired to reverse the engine, it is necessary to swing the reverse lever 47 about its pivotal mounting 48 to shift the slide 44 from one end of the slot 43 in the rocker segment to the opposite end thereof. This movement is transmitted to the cams 32 which control the auxiliary poppet valves 29 15 by a lever 49 having a pivotal mounting 50 intermediate its ends. The upper end of the lever 49 is slotted as indicated at 51, to provide a lost motion connection with the pin 52 of the slide 44. The lower end of the lever 20 49 is similarly adapted through a lost motion connection 53 to reciprocate the rod 54. This rod 54 is provided adjacent one end with anti-friction rolls 55 spaced to straddle the collar 56 on the sleeve 33. By reason of this connection, it will be apparent that movement of 25 the reversing lever 47 will be effective for reciprocating the rod 54 and consequently the sleeve 33. The reciprocating movement of the sleeve 33 is converted into rotary motion 30 for advancing the cam 32 substantially 180° by providing a high pitch thread 57 on the end of the cam shaft 34 adapted to mesh with a similar thread 58 on the interior of the sleeve 33. This mechanism is also duplicated 35 for each end of the engine.

In Figure 4 I have illustrated the piston 23 as having just completed its travel toward the right-hand end of the cylinder 20. Continued operation of the engine will result in 40 opening the poppet valve 27 to admit live steam to the right-hand end of the cylinder 20 for moving the piston to the left. During such movement, if it is desired to reverse the engine, the reversing lever 47 will be operated as described. This will result in closing 45 the valve 27 and opening the valve 25. At the same time, it will result in opening the auxiliary valve 29 at the right-hand end of the cylinder. Immediately upon the opening 50 of the valve 29 trapped steam which was undergoing expansion in the right-hand end of the cylinder will escape by the valve 29 into the chamber 14' and then past the valve 15' either to the condenser or to the atmosphere. It will be understood that the valve 55 15' may be constructed as described in detail in connection with Figures 1 and 2.

In Figure 7 there is illustrated diagrammatically the indicator card having a curve 60 thereon for each end of the cylinder, the curves being arranged in comparative relationship. For sake of brevity, I have illustrated the points on the curves with the same reference letters used in describing Figure 3, 65 with a prime affixed thereto. In this figure,

however, I have illustrated by the chain line K the drop in pressure which will occur if the engine is reversed at the point L.

Now assume that it is desired to reverse the engine at a time when the piston is moving 70 toward the right hand end of the cylinder under the influence of steam admitted by the valve 25. The pressure condition in the right hand end of the cylinder will be represented by a point on the compression line of the indicator card, the particular location of this point depending upon the position of the piston at the time the reversing is effected. Assume that it is at the point M. The valve 29 at the left hand end of the cylinder will 75 of course be open and the pressure in the left hand end will drop. At the same time steam will be admitted to the right hand end and the pressure curve would be represented by at least a part of the chain line extending upwardly from the point M in Figure 7. The maximum pressure which would be shown on an indicator card for this particular stroke is immaterial to the operation of the engine, but it will be understood that the pressure 80 will tend to rise to the maximum inlet pressure. It may not reach such maximum pressure due to closing of the inlet valve within a very short period of time but in any event the pressure will rise to such a point that the 85 piston will be stopped and will commence a return travel without completing its stroke, thus reversing the engine.

It will be understood that knowing the conditions in one end of the cylinder, the conditions in the opposite end of the cylinder may 90 be readily determined by drawing perpendicular lines from any point in the upper line of the power curve for the right-hand end of the cylinder to the lower line of the power curve for the left-hand end of the cylinder, it being necessary to have a condition of compression on one side of the piston while expansion is taking place on the opposite side and vice versa. It will also be understood 95 that during the normal operation of the engine, the opening of the auxiliary valves 29 will not permit any escape from the cylinder as the cams 32 will be timed to produce such opening movement at a point in the power curves below the line G'. During such time, as the pressure in the cylinder will be less than the pressure at which the relief valves are set to open, pressure conditions within the cylinder 100 will not be affected by the relief valves.

While I have illustrated a preferred embodiment of my invention, both in connection with a piston valve uniflow motor and a poppet valve uniflow motor, various changes may be made in the construction and operation of the motor without departing from the spirit of my invention or scope of my broader claims. The invention may also be applied to other types of uniflow motors as desired.

The advantages of the present invention

arise from the provision of means permitting the reversal of a uniflow engine at any time during the operation thereof, such mechanism including means for releasing the 5 trapped steam from one end of the engine cylinder.

I claim:

1. In a uniflow engine, mechanism for reversing the same, said mechanism including 10 means for relieving trapped steam from the engine, a steam passage leading from the cylinder to said means, and a controlling valve effective for closing off said passage so as to prevent escape of steam during normal engine operation, but movable upon reversal of the engine before exhaust takes place to open the passage and permit of escape of steam through said means when it is desired to reverse the engine.
2. In a uniflow engine, mechanism for reversing the same, said mechanism including a valve adapted to open when subjected to relatively low steam pressure, a steam passage from the cylinder to said valve, and a 25 controlling valve effective for closing off said passage so as to prevent escape of steam during normal engine operation, but movable upon reversal of the engine before exhaust takes place to open the passage and permit 30 of escape of steam through the first mentioned valve when it is desired to reverse the engine.
3. In a uniflow engine, mechanism for reversing the same, said mechanism including 35 a spring loaded valve adapted to open the relatively low steam pressure, a steam passage from the cylinder to said spring loaded valve, and a controlling valve effective for closing off said passage so as to prevent es-

cape of steam during normal engine operation, but movable upon reversal of the engine before exhaust takes place to open the passage and permit of escape of steam through said 40 spring loaded valve when it is desired to reverse the engine.

4. In a uniflow engine, mechanism for reversing the same, said mechanism including a loaded relief valve for the escape of trapped steam from the engine, means for regulating the pressure at which said valve opens, a 50 steam passage from the cylinder to said relief valve, and a controlling valve effective for closing off said passage so as to prevent escape of steam during normal engine operation, but movable upon reversal of the engine before exhaust takes place to open the passage and permit escape of steam through the 55 first mentioned valve when it is desired to reverse the engine.

5. In a uniflow engine, a cylinder, a piston, 60 means controlling the admission of steam to each end of the cylinder, and mechanism for reversing the engine, said mechanism including means for releasing trapped steam from an end of the cylinder, a steam passage from 65 the cylinder to said means, said means for controlling the admission of steam being further adapted for closing off said passage so as to prevent escape of steam through said releasing means during normal engine operation, but movable upon reversal of the engine before exhaust takes place to open the passage and permit of escape of steam through said means when it is desired to reverse the 70 engine.

In testimony whereof I have hereunto set my hand.

JULIAN KENNEDY.
